UNITED STATES PATENT OFFICE.

THEODOR WEYMERSKIRCH, OF DIFFERDINGEN, LUXEMBURG, AND LOUIS CHAVANNE,
OF PARIS, FRANCE.

PROCESS FOR CASTING CYLINDRICAL BODIES.

Application filed April 23, 1926, Serial No. 104,167, and in Germany April 20, 1925.

This invention has for its object improvements in methods of casting, castings and molds for casting or molding grooved rolls, cylinders or other similar bodies, especially 5 bodies of cylindrical shape made of chilled iron.

Molds for such castings are already known which comprise several rings fitting into each other and which are maintained 10 in position during the casting operation by means of bolts or similar devices, the said rings being freed by an operator when the casting shrinks, in order to allow the rings to follow the shrinkage movement. This 15 handling takes place by moving conveniently the setting devices of the frames to which the rings are secured.

As the loosening of the rings is made under man supervision and by hand, it is not 20 certain that it always occurs at the right time: that is in such a way as to insure free shrinkage of the metal cast in; very often indeed the regular moment has elapsed and it occurs that the shrinkage of the casting 25 is impeded and consequently it results that rings and casting break in several pieces.

For preventing the above causes of failure, the present invention has been devised; it utilizes the effects upon the mold of metal 30 expansion and contraction, accompanying the phenomenon of its solidification (after it is cast in). It is well known, indeed, that different phases characterize the new physical state of cast metal when it becomes solid. 35 There comes first the phase of expansion (corresponding for iron to the separation of carbon under the form of free graphite); then a phase, very short, when the volume does not change, followed by the contraction phase, during which shrinkage occurs.

Each one of these successive phases can be 40 of various but short duration: thence, the difficulty after casting chilled rolls in chill rings mold, of a quick and accurate "modus operandi" for slackening at proper time the mold system, if such modus operandi does not take care of the values of expansion and shrinkage, which are at variance almost in each case owing to certain conditions affecting elements like: composition of the metal, casting temperature, speed of cooling, etc. It must be remarked that owing to their contact with the very hot roll, chill rings molds are also subjected to more

or less dilation, but this action is practically 55 negligible.

One way to insure freedom for the expansion and the contraction of a roll cast within a mold made of a convenient number of chill rings suitably positioned, is to allow 60 simultaneous freedom of each chill ring; consequently, linking and setting devices of the chill rings such as link bars or rods, wedges, etc., should be so made, arranged and combined together with the rings, that 65 they sustain the effects of expansion or of shrinkage (or of both) of the roll, and that under said action they shall be disengaged, disconnected, removed or thrown out, either automatically or semi-automatically and as 70 those effects proceed; thus insuring simultaneously the freedom of the rings which then could not impede, in any case, the movements of the roll.

As previously the mould is formed of a 75 series of superimposed sized rings which, as known, are jointed on their inner surface by rings and are centrally maintained and axially guided by embedded circular rings or bands, linking devices being interposed 80 between two consecutive mould rings the tension of which may be varied in order to provide an appropriate relative position of the mould parts.

The linking devices are provided with 85 means for insuring a quick and reliable freeing of the mould before the casting expands and the said freeing takes place according to the invention half automatically or automatically during the period of expansion by 90 means of the movements of the mould itself. The invention allows of casting grooved rolls with a great degree of precision and with certainty.

The accompanying drawings show by 95 way of example various embodiments of the invention.

In these drawings:

Fig. 1 shows a diametrical section of a mold according to this invention.

Fig. 2 is a portion of a side view of the device shown in Fig. 1 with the slackening device and an electrical alarm device.

Fig. 3 shows at a larger scale a cross section through a linking device of Figs. 1 105 and 2.

Figs. 4 to 26 show modifications.

As shown in Figs. 1 to 3 the mould com-

prises an upper mould 1 for the trunnions of a mill roll, a chill mould 2, and a lower trunnion mould 3. The chill mould 2 is vertically and horizontally divided in several parts in order to follow the expansion of a fresh cast roll. To that purpose plays 4 are provided between the parts of the mould. These plays are obtained by means of linking devices 5 such as eccentric bolts, 10 taper-screw bolts, taper-chocks or the like. These linking devices are intended to act between two moulding pieces in such a way that each moulding piece acts on a rest for the next one.

15 In order to prevent the molten iron from entering the plays the mould pieces are provided with recesses 6 in which a sand ring or an oil core is placed. The recesses 6 are funnel shaped towards the outside which 20 gives the ring 7 an opportunity to follow the movements of the mould pieces and to penetrate in the space 8. These rings 7 may be made very broad or very narrow as they are not submitted to any pressure by the 25 mould pieces.

When building the mould the linking pieces 5 of the mould parts are placed in a convenient manner. Unevennesses may 30 be avoided by accurately placing the linking pieces 5. The linking pieces are connected by means of appropriate devices such as transmission rods 9 (Figs. 1, 2, 5, 6, 9, 10, 11, 12, 15, 17, 19 and 21) which are carried and maintained in position by 35 a ring 10. The said ring is advantageously located at the upper part of the mould in order to be used simultaneously for a great number of moulding rings depending from a common upper mould part.

40 The controlling device may be realized by way of example in the form of a ring 10 located around the mould part 1 and movable on rollers 11. The transmission rods 9 provided with roller 12 and weights 45 13 rest on this ring 10.

When the mould is to be slackened the ring 10 is drawn towards the right of Fig. 2 by means of a hook 14, from which it results that the transmission rods 9 come 50 down owing to their own weight and to the weight of the weights 13. This has the effect of slackening the linking devices through the levers 15 (Figs. 1, 2) or the pinions 15 (Figs. 4-6). The downward movement of the rods 9 is limited by buffers 55 16 (Figs. 1, 2).

In order to avoid any shock in the downward movements of the rods 9, the ring 10 is provided with inclined planes 17 (Fig. 60 2) on which the rollers 12 of the rods 9 come down gently.

The linking device shown on Fig. 3 is formed of an oval or eccentric bolt 18 which acts between two bearings 19 carried by 65 the mould rings.

On Figs. 4 and 5 the linking devices are taper-thread bolts 20 acting between two threaded wedges 21 located themselves between two wedges 22-23, the mould rings 24 having also tapering upper and lower 70 surfaces. The bolts 20 are rotated by means of the pinions 15 acted upon by racks carried by the rods 9.

On Figs. 6, 7 and 8 a linking device is shown as made of three wedges 26, 27, 28 75 the wedge 28 being drawn outwardly by the eccentric pinion 15 meshing with the rack of the rod 9.

On Fig. 9 the linking devices comprise wedges 29 and 30, the latter being moved 80 outwardly by a lever 31, 32 linked to the rod 9 by an arm 15.

On Fig. 10 the wedges 29, 30 are replaced by a roller or a ball 33 and on Fig. 11 the lever 32 is provided with a hinged piece 34. 85

The mould rings are guided by embedded rings 35 (Fig. 10) or by iron pieces 36 or rings 36. These rings 36 are provided with apertures 37 (Fig. 16) through which the linking devices are placed and also with 90 apertures 38 in order to allow the gases to escape.

An electric alarm device may be provided in order to give notice of the time at which the mould ought to be slackened 95 (Fig. 2). For this purpose the expansion of the pig iron and consequently of the mould is used. As shown in Fig. 2 the upper part 1 of the mould is connected to the contact 39 of an electrical bell 40. 100 When the mould expands axially the contact 39 touches the fixed contact piece 41 and the bell rings gives notice that the mould ought to be slackened.

The slackening of the mould may be entirely automatically done either by means of electromagnets 42 (Fig. 12) coupled by links 44 to the rods 9 and worked by an electric current supplied by means of a relay 48, 49, 50, 51 in which current is sent by the 110 contacts 46, 47. An interrupter 54 acted upon by the finger 53 cuts the current from the magnets 43 when the linking devices have worked.

As shown in Figs. 13 and 14 the electromagnets 55 may act directly on the linking devices (left part of the figure) or the electromagnets 58 may act simultaneously on a grooved bar 58 to which the linking devices 57 are secured. 115

Instead of being moved by electricity the rods 9 can be moved, as on Fig. 15, by means of a fluid under pressure acting in a cylinder 71 through a cock 70 open by a piston 69 under which pressure fluid is admitted 125 in 68 through 67 by means of a valve 66 lifted by the mould acting on the rod 64 and the buffer 65. The fluid is admitted from a main 59 to the valve through 61, 62 and 63 and to the cylinder 71 through 60. 130

On Fig. 16 the device for slackening the mould parts is similar as the one shown in Figs. 1 and 2 but the ring 10 is moved through an arm 14 by a rod 74 the collar 80 of which is pushed by a spring 79, located in a cylinder 73, when the arrest 75 is repelled by the expanding mould through 64 and liberates the notch 78 of the rod 74. A pinion 77 worked by hand allows the device to be replaced in operating position. Contacts as 81 and 82 may be carried by the rod 74 and by the cylinder 73 in order to electrically actuate electromagnets such as the ones shown on Fig. 12.

Figs. 17, 18, 19, 20, 21 and 22 show other means of actuating the linking devices of the mould parts. On Figs. 17, 18 and 19, a single rod 9 acts on two pairs of linking bolts 86 turning between bearings 84, 85, by means of transverse bars normally locked by locks 89, 92 acting on recesses 91 and 92. On Fig. 20 the bolt 86 is replaced by two wedges 93 brought together or apart by the threaded rod 94. On Figs. 21 and 22 the linking devices 57 are moved by rollers 100 and inclined planes 99 carried by the stem 97 the rollers 100 being rotatably mounted on a slide 98.

On Figs. 23, 24 and 25 the linking devices 57 are carried by rods 101 hinged on cranks 102 secured on rods 9 provided with pinions 15 meshing with toothed segments 107 mounted on a ring rotatable around the lower part 3 of the mould. This ring is rotated by an electro-magnet 103, a rod 104 and a socket 105. The electro-magnet is supplied with current by the contacts 46, 47 and the relays 48, 49, 50, 51, 52. A bell 40 is also provided as previously explained. The current in the electro-magnet is cut by the finger 53 acting on the interrupter 54. A lever 108 allows of operating the device by hand or replacing it in its original position.

It is obvious that the linking devices may be placed between sockets provided on the mould rings instead of being located between said rings.

Moreover, the main feature of the present invention, that is the self-slackening of the composite ring mold, provoked automatically or semi-automatically by the motion of the casting at the right time during the early period of the solidification of its metal, is also essential as previously explained for preventing distortions or even breakage of the mold members and of the cast body.

The tools, apparatus, devices, their various arrangements and combinations with the chill ring such as hereinbefore described, fully answer the purpose of the invention; however, they are given here only as mere illustrations of various forms of suitable

means for carrying out the process and we do not intend to limit to it the means illustrated.

What we claim is:

1. A process for casting cylindrical bodies in a mold formed by a plurality of mold members which includes maintaining the mold members in predetermined positions during the casting operation, and in employing the change in volume of the casting, during the period of solidification of the same, to release said mold members, thereby permitting the cast body to freely contract without breaking or distortion of said mold members.

2. A process for casting cylindrical bodies in a mold formed by a plurality of mold members which are maintained in predetermined spaced relation by linking devices, which includes positively retaining said mold members in a predetermined position during the casting operation, and moving said linking devices by the axial, expansive movement of the cast body, during the solidification period thereof, to free said mold members from said predetermined position.

3. A process for casting cylindrical bodies in a mold formed by a plurality of superimposed mold members, which includes positively maintaining the mold members in spaced apart relation during the casting operation, and in employing the change in volume of the casting, during the period of solidification of the same, for actuating signal means to give notice of the axial movement of said mold members.

4. A process for casting cylindrical bodies in a mold formed of a plurality of mold members which are maintained in spaced relation by linking devices, which consists in maintaining said linking devices stationary during the casting operation to prevent relative movement of the mold members, moving said linking devices by the change in volume of the casting, during the solidification period, to permit relative movement of the mold members and simultaneously employing said change in volume to actuate a signal device.

5. A method for controlling a plurality of mold members employed in casting cylindrical bodies which consists in holding said members in spaced relation during the casting operation, and employing the change in volume of the metal casting, during the period of solidification of the same, to release said mold members, thereby permitting free contraction of the casting.

In testimony whereof we have affixed our signatures.

LOUIS CHAVANNE.
THEODOR WEYMERSKIRCH.
